DESIGN FOR A POWER DRIVEN LAWN TRIMMER

Leonard B. Goodall, Warrensburg, Mo.

Application July 30, 1945, Serial No. 121,079

Term of patent 14 years

(Cl. D40—1)

To all whom it may concern:

Be it known that I, Leonard B. Goodall, a citizen of the United States, residing at Warrensburg, in the county of Johnson and State of Missouri, have invented a new, original, and ornamental Design for a Power Driven Lawn Trimmer, of which the following is a specification, reference being had to the accompanying drawings, forming a part thereof.

Fig. 1 is a front elevational view of the power driven lawn trimmer, showing my new design.

Fig. 2 is a side elevational view thereof with a portion of the handle broken away for convenience of illustration.

Fig. 3 is a top plan view thereof with a portion of the handle broken away for convenience of illustration; and

Fig. 4 is a side elevational view of the power driven lawn trimmer, showing the side opposite to that illustrated by Fig. 2, with a portion of the handle broken away for convenience of illustration.

I claim:

The ornamental design for a power driven lawn trimmer, as shown.

LEONARD B. GOODALL.
